RAILWAY TRAFFIC CONTROLLING
APPARATUS

Charles A. Brooks, Forest Hills, N. Y., assignor to
The Union Switch & Signal Company, Swiss-
vale, Pa., a corporation of Pennsylvania

Application June 7, 1934, Serial No. 729,392
Renewed March 23, 1936

12 Claims. (Cl. 246—141)

My invention relates to railway traffic controlling apparatus, and particularly to apparatus of the type comprising a railway switch controlled by a manually operable lever, together with means for indicating the position of the switch and of its operating mechanism.

One object of my invention is the provision, in apparatus of the type described, of novel and improved means for utilizing the switch control wires as part of the circuit for the indicating means.

I will describe one form of railway traffic controlling apparatus embodying my invention, and will then point out the novel features thereof in claims.

The accompanying drawing is a view, partly diagrammatic, illustrating one form of railway traffic controlling apparatus embodying my invention.

Referring to the drawing, the reference characters 1 and 1^a designate the rails of a stretch of railway track provided with a switch 2. This switch is operated by a fluid pressure motor A comprising a cylinder 3 containing a reciprocable piston 4. Attached to the piston 4 is a piston rod 5 which is operatively connected with the movable points of the switch 2 through suitable mechanism which is indicated by the dotted line 5^a.

The motor A is controlled by a switch valve C comprising a slide valve 7 operating in a valve chamber 6. The chamber 6 is constantly supplied with fluid pressure, from a source not shown in the drawing, through pipe 11. When the slide valve is in its normal position, fluid pressure is supplied from chamber 6, through pipe 10 to the lower end of cylinder 3 of motor A, and the upper end of this cylinder is connected with atmosphere through pipe 8 and port 9. With the valve in this position, therefore, the piston 4 is moved upwardly and the switch then occupies its normal position. When the slide valve 7 occupies its reverse position, pipe 8 is connected with chamber 6, and pipe 10 is connected through ports 9 to atmosphere. The piston 4 is then driven downwardly and the switch 2 is moved to its reverse position.

The valve 7 is provided with two spaced notches 15 and 16 one or the other of which receives a locking rod 17 according as the valve is in the reverse or normal position. The rod 17 carries an armature 18 associated with a lock magnet winding 19, and is constantly urged toward the slide valve 7 by a spring 20. When winding 19 is energized, however, armature 18

is moved outwardly, thereby disengaging the rod 17 from the notch in the slide valve and permitting the valve to be shifted by means which I will describe hereinafter. It will be plain, however, that the valve can be shifted only when winding 19 is energized to draw the rod 17 out of the notch in the valve.

The switch valve C also comprises two oppositely disposed axially aligned cylinders 12 and 12^a. The cylinder 12 contains a piston 13 carrying a stem 14 which engages one end of the slide valve 7, and the cylinder 12^a contains a piston 13^a carrying a stem 14^a which engages the other end of the slide valve 7. Cylinder 12 is at times supplied with fluid pressure by a valve 21 comprising a valve stem 23 provided with a reverse magnet winding 25 and an armature 24 associated therewith. When winding 25 is de-energized the valve stem 23 occupies its right-hand position and cylinder 12 is connected with atmosphere. When winding 25 of valve 21 is energized, however, the valve stem 23 is moved to the left and cylinder 12 is then disconnected from atmosphere and is connected with a source of fluid pressure. In similar manner, a valve 22 controls the supply of fluid pressure to cylinder 12^a so that when normal magnet winding 25^a of valve 22 is de-energized, cylinder 12^a is connected with atmosphere, but that when this winding is energized cylinder 12^a is supplied with fluid pressure. It will be plain from the drawing that when cylinder 12^a is supplied with fluid pressure, piston 13^a is moved upwardly to drive the valve 7 to its normal position. When cylinder 12 is supplied with fluid pressure, however, piston 13 moves downwardly and drives the valve 7 to its reverse position. In either case, of course, movement of valve 7 is possible only if the locking rod 17 is withdrawn from the notch 15 or 16.

The windings 25 and 25^a of valves 21 and 22 and winding 19 are controlled by a manually operable lever L. This lever comprises a handle 33 and a plurality of contacts arranged to be open or closed in accordance with the position occupied by this handle. The diagram appearing immediately below the handle 33 in Fig. 1 illustrates the principal positions which may be occupied by the lever. These positions are: full normal or left-hand position N, full reverse or right-hand position R, and two intermediate positions known as the reverse indicating position D and the normal indicating position B. The various contacts are designated by the reference characters which correspond to this diagram and which indicate the

55

positions in which the associated contacts are closed. For example, the lowest contact on the lever L is designated by the reference character NB, which means that this contact is closed when 5 the lever L is in the normal position, the B position, or any position between these two.

The circuit for lock magnet winding 19 may be traced from terminal B of a suitable source of current, through back contact 37 of an indication relay E, and winding 19 to terminal O of the same 10 source of current. The circuit for reverse magnet winding 25 passes from terminal B, through wire 70, contact DR of lever L, wire 71, and winding 25 of valve 71 to terminal O. When contact NB 15 of lever L is closed, current flows from terminal B, through wire 72, contact NB of lever L, wire 73, and normal magnet winding 25^a of valve 22, to terminal O.

Associated with lever L are a normal indication 20 lock K and a reverse indication lock J. Each of these indication locks comprise a segment 36 operatively connected with the lever L, and a magnet 34 having a locking dog 35 controlled thereby. Segment 36 of lock K is provided with a projection 25 36^a so arranged that when the lever is moved from the reverse position toward the normal position, the dog 35 engages the projection 36^a and prevents movement of the lever past the normal indicating position B unless magnet 34 of lock K 30 is energized. In similar manner, segment 36 of lock J is provided with a projection 36^b which is arranged to be engaged by the dog 35 at the D position when the lever is moved from the normal position toward the reverse position, unless the 35 associated magnet 34 is energized. The magnets 34 of the indication locks K and J are controlled by the polarized indication relay E, and by contacts on the lever L. The circuit for the magnet of lock K passes from terminal B, through front 40 contact 56 of relay E, wire 57, normal contact 58 of relay E, wire 59, contact RB of lever L, wire 60, and magnet 34 of lock K to terminal O. The reverse locking circuit passes from terminal B, through front contact 56 of relay E, wire 57, reverse 45 contact 63 of relay E, wire 64, contact ND of lever L, wire 65, and magnet 34 of lock J, to terminal O.

The apparatus thus far referred to is described and illustrated in United States Letters Patent No. 50 1,718,169, granted to J. P. Coleman on the 14th day of May, 1929, for Railway traffic controlling apparatus.

The polarized indication relay E is supplied with current over the two control wires 71 and 73, and 55 is controlled by two circuit controllers G and H. Circuit controller G is connected with the switch 2 and the operating mechanism for this switch by suitable mechanism indicated by the dash line 5^a. Circuit controller H is operated by the slide 60 valve 7 through suitable mechanism indicated by the dash line 7^a.

When the lever L and the slide valve 7 and the switch 2 are all in their normal positions, relay E is supplied with current of normal polarity 65 through a circuit which passes from terminal B, through wires 72, lever contact NB, wires 73 and 39, contact 27-27^b, contact 29-29^a, winding of relay E, and contact 30-30^a to terminal O. Relay E is then energized in the normal direction, 70 so that its contacts 56 and 58 are closed.

When the lever L is in its reverse position and both the slide valve 7 and the switch 2 occupy their reverse positions, relay E will be supplied with current of reverse polarity, the circuit being 75 from terminal B, through wire 70, lever-operated

contact DR, wires 71 and 38, contact 28-28^a, contact 31-31^a, winding of relay E and contact 32-32^a to terminal O. Relay E will then be energized in the reverse direction, so that its contacts 56 and 63 will be closed. 5

If the slide valve 7 is in the normal position and switch 2 is in the reverse position, relay E will be shunted through contacts 28-28^b and contact 31-31^a. If the slide valve is in the reverse position and the switch is in the normal position, 10 relay E will be shunted by contacts 27-27^a and 29-29^a.

As shown in the drawing, the lever L occupies its normal position, so that normal magnet winding 25^a is energized and relay E is energized in 15 the normal direction. Cylinder 12^a is therefore supplied with fluid pressure and valve 7 occupies its normal position. Back contact 37 of relay E is open, so that lock winding 19 is de-energized and rod 17 therefore projects into groove 16 to 20 lock the slide valve in normal position. Since valve 7 is in its normal position, fluid pressure is supplied to the lower end of cylinder 3 of motor A and the switch 2 occupies its normal position. I will now assume that the operator in 25 charge of lever L wishes to reverse switch 2. Lever L is first moved toward the reverse position. Magnet 34 of the reverse indication lock J is de-energized, so that movement of the lever is arrested at the D position. The movement 30 of the lever from the N to the D position, de-energizes normal magnet winding 25^a and energizes reverse magnet winding 25. This movement of the lever also de-energizes the indication 35 relay E, so that the circuit for the lock magnet 19 becomes closed at back contact 37. Cylinder 12 will now be supplied with fluid pressure and cylinder 12^a will be connected with atmosphere, and valve 7 will therefore be moved to its reverse position by piston 13. The reversal 40 of slide valve 7 will connect the lower end of cylinder 3 with atmosphere, and will supply fluid pressure to the upper end of this cylinder. The switch 2 will therefore be moved to its reverse position. When the switch has attained its full 45 reverse position, circuit controllers G and H will complete the reverse circuit for relay E, and the closing of reverse contact 63 of this relay will complete the circuit for magnet 34 of lock J. Dog 35 of this lock will therefore be lifted to 50 permit lever L to be moved to its full reverse position R. Contact ND will then become opened, and the opening of this contact will de-energize the magnet 34 of lock J. 55

The operation of the apparatus during the return of the switch 2 to its normal position will be understood from the foregoing without detailed explanation.

Although I have herein shown and described 60 only one form of apparatus embodying my invention, it is understood that various changes and modifications may be made therein within the scope of the appended claims without departing from the spirit and scope of my invention. 65

Having thus described my invention, what I claim is:

1. In combination, a railway track switch, an operating mechanism for said switch including a 70 normal magnet and a reverse magnet, a normal control wire connected with said normal magnet and a reverse control wire connected with said reverse magnet, means located at a remote point for connecting one or the other of said wires 75

with one terminal of a source of current, a polarized indication relay, and means operating when said switch is in normal position to connect one terminal of the winding of said relay with said one terminal of said source through said normal wire and the other terminal of the relay winding with the other terminal of said source, said means operating when the switch is in reverse position to connect the second terminal of said 10 relay winding with said one terminal of said source through said reverse wire and the first terminal of the relay winding with said other terminal of said source.

2. In combination, a railway track switch, a fluid pressure motor for operating said switch, a slide valve for admitting fluid pressure to said motor to move the switch to normal or reverse position according as the slide valve is in its normal or reverse position, a normal magnet and 15 a reverse magnet for controlling said slide valve, a normal control wire connected with said normal magnet and a reverse control wire connected with said reverse magnet, means located at a remote point for connecting one or the other 20 of said wires with one terminal of a source of current, a polarized indication relay, and means operating when and only when said switch and said slide valve are both in normal position to connect one terminal of the winding of said relay 25 with said one terminal of said source through said normal wire and the other terminal of the relay winding with the other terminal of said source, said means operating when and only when the switch and the slide valve are both in 30 reverse position to connect the second terminal of said relay winding with said one terminal of said source through said reverse wire and the first terminal of the relay winding with said other terminal of said source.

3. In combination, a railway track switch, a normal control magnet and a reverse control magnet for said switch, a manually controllable circuit for energizing said normal control magnet, a second manually controllable circuit for 35 energizing said reverse control magnet, a polarized indication relay, an indication circuit energized by current from said first manually controllable circuit and controlled by said normal control magnet and by said switch for energizing said polarized indication relay by current of normal polarity if said normal control magnet is energized and if said switch is in the normal position, a second indication circuit energized by current from said second manually controllable 45 circuit and controlled by said reverse control magnet and by said switch for energizing said polarized indication relay by current of reverse polarity if said reverse control magnet is energized and if said switch is in the reverse position, and means controlled by energization of said normal control magnet to operate said switch to the normal position and by energization of said reverse control magnet to operate said switch to the reverse position.

4. In combination, a railway track switch, a normal control magnet and a reverse control magnet for said switch, a manually controllable circuit for energizing said normal control magnet, a second manually controllable circuit for 50 energizing said reverse control magnet, a polarized indication relay, an indication circuit energized by current from said first manually controllable circuit and controlled by said switch for energizing said polarized indication relay by current of normal polarity if said switch is in the 55

normal position, a second indication circuit energized by current from said second manually controllable circuit and controlled by said switch for energizing said polarized indication relay by current of reverse polarity if said switch is in the 5 reverse position, and means controlled by energization of said normal and reverse control magnets for operating said switch to normal and reverse positions respectively.

5. In combination, a railway track switch, a 10 normal control magnet and a reverse control magnet for said switch, a two-position circuit controller operable to a normal position in response to energization of said normal control magnet and operable to a reverse position in 15 response to energization of said reverse control magnet, a manually controllable circuit for energizing said normal control magnet, a second manually controllable circuit for energizing said reverse control magnet, a normal indication circuit 20 receiving energy from said first manually controllable circuit and closed by operation of said switch and said two-position circuit controller to their normal positions, a reverse indication circuit receiving energy from said second 25 manually controllable circuit and closed by operation of said switch and said two-position circuit controller to their reverse positions, normal and reverse indication means controlled by said 30 normal and reverse indication circuits respectively, and means responsive to energization of said normal and reverse control magnets to operate said switch to its normal and reverse positions respectively.

6. In combination, a railway track switch, a 35 normal control magnet and a reverse control magnet for said switch, a manually controllable circuit for energizing said normal control magnet, a second manually controllable circuit for energizing said reverse control magnet, a normal 40 indication circuit energized by current from said first manually controllable circuit only if said switch is in the normal position, a reverse indication circuit energized by current from said second manually controllable circuit only if said 45 switch is in the reverse position, normal and reverse indication means controlled by said normal and reverse indication circuits, and means controlled by said normal and reverse control magnets when energized to operate said switch to the 50 normal and reverse positions respectively.

7. In combination, a railway track switch, a manually controllable normal control circuit for said switch, a manually controllable reverse control circuit for said switch, normal indication 55 contact means closed in response to energization of said normal control circuit, reverse indication contact means closed in response to energization of said reverse control circuit, normal switch contact means closed by operation of said switch 60 to the normal position, reverse switch contact means closed by operation of said switch to the reverse position, a normal indication circuit energized by current from said normal control circuit and controlled by said normal indication 65 contact means and said normal switch contact means, a reverse indication circuit energized by current from said reverse control circuit and controlled by said reverse indication contact means and said reverse switch contact means, normal and reverse indication means controlled by said indication circuits, means controlled by said normal and reverse control circuits and by said switch for shunting 70 said indication means if the position of said 75

- switch does not agree with the condition of said normal and reverse control circuits, and means responsive to energization of said normal and reverse control circuits for operating said switch to the normal and reverse positions respectively.
8. In combination, a railway track switch, a manually controllable normal control circuit for said switch, a manually controllable reverse control circuit for said switch, normal indication contact means closed in response to energization of said normal control circuit, reverse indication contact means closed in response to energization of said reverse control circuit, normal switch contact means closed by operation of said switch to the normal position, reverse switch contact means closed by operation of said switch to the reverse position, a normal indication circuit energized by current from said normal control circuit and controlled by said normal indication contact means and said normal switch contact means, a reverse indication circuit energized by current from said reverse control circuit and controlled by said reverse indication contact means and said reverse switch contact means, normal and reverse indication means controlled by said indication circuits, means controlled by said normal and reverse control circuits and by said switch for shunting said indication means if said switch occupies its normal position with said reverse indication contact means closed or if said switch occupies its reverse position with said normal indication contact means closed, and means responsive to energization of said normal and reverse control circuits for operating said switch to the normal and reverse positions respectively.
9. In combination, a railway track switch, a manually controllable normal control circuit for said switch, a manually controllable reverse control circuit for said switch, means controlled by said normal and reverse control circuits for operating said switch to normal and reverse positions respectively, a normal indication circuit energized by current from said normal control circuit only if said switch occupies the normal position, a reverse indication circuit energized by current from said reverse control circuit only if said switch occupies the reverse position, indication means controlled by said normal and reverse indication circuits, and means controlled by said switch and by said normal and reverse control circuits for shunting said indication means if said switch fails to occupy a position corresponding to the energization of said normal and reverse control circuits.
10. In combination, a railway track switch, a manually controllable normal control circuit for

said switch, a manually controllable reverse control circuit for said switch, means controlled by said normal and reverse control circuits for operating said switch to normal and reverse positions respectively, a normal indication circuit energized by current from said normal control circuit only if said switch occupies the normal position, a reverse indication circuit energized by current from said reverse control circuit only if said switch occupies the reverse position, indication means controlled by said normal and reverse indication circuits, and means controlled by said switch and by said normal and reverse control circuits for shunting said indication means if said switch occupies its normal position while the reverse control circuit is energized or if said switch occupies its reverse position while the normal control circuit is energized.

11. In combination, a railway track switch, a normal conductor, a reverse conductor, a common conductor, a normal control device, a reverse control device, a manually controllable circuit including said normal and common conductors for effecting operation of said normal control device, a second manually controllable circuit including said reverse and common conductors for effecting operation of said reverse control device, means controlled by said normal and reverse control devices for operating said switch to its normal and reverse positions respectively, a normal indication circuit energized by current from said first manually controllable circuit only if said switch occupies the normal position, a reverse indication circuit energized by current from said second manually controllable circuit only if said switch occupies the reverse position, and normal and reverse indication means controlled by said normal and reverse indication circuits.

12. In combination, a railway track switch, a normal conductor, a reverse conductor, a common conductor, a manually controllable circuit including said normal and common conductors for effecting operation of said switch to its normal position, a second manually controllable circuit including said reverse and common conductors for effecting operation of said switch to its reverse position, a normal indication circuit energized by current from said first manually controllable circuit only if said switch occupies the normal position, a reverse indication circuit energized by current from said second manually controllable circuit only if said switch occupies the reverse position, and normal and reverse indication means controlled by said normal and reverse indication circuits.

CHARLES A. BROOKS.
